HARTFORD CARPET COMPANY, OF HARTFORD, CONNECTICUT.

DESIGN FOR A CARPET.

SPECIFICATION forming part of Design No. 12,465, dated September 13, 1881.

Application filed August 9, 1881. Term of patent 3½ years.

To all whom it may concern :

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

A is a fanciful rosette; B, a cross-shaped figure. C D E are rosettes; E' F G H, flower-like figures. These figures, together with numerous others, are by a series of bars united into a *quasi* net-work that covers the background of the carpet. The background is com-

posed of series of hexagons, *a a*, each containing a smaller hexagon, within which is a cross. 20

I claim—

1. The design for the background of a carpet, the same being composed of hexagons *a a*, each containing a smaller hexagon, within which is a cross, substantially as shown. 25

2. The design for a carpet, composed of the figures A B C D E E' F G H and connecting bars and figures, substantially as shown.

3. The design for a carpet, composed of the figures A B C D E E' F G H, their connecting 30 bars and figures, and of the figures *a*, substantially as shown.
